UNITED STATES PATENT OFFICE.

EMANUEL AUFIERO, OF BROOKLYN, NEW YORK.

DESIGN FOR A WARNING-SIGNAL.

41,747.

Specification for Design.

Patented Sept. 5, 1911.

Application filed May 11, 1911. Serial No. 626,595. Term of patent 7 years.

To all whom it may concern:

Be it known that I, EMANUEL AUFIERO, a citizen of the United States, residing at Brooklyn, in the county of Kings and State of New York, have invented a new, original, and ornamental Design for a Warning-Signal, of which the following is a specification, reference being had to the accompanying drawing, forming part thereof.

The figure is a side elevation showing the design of the article.

I claim:

The ornamental design for a warning signal, as shown.

EMANUEL AUFIERO.

Witnesses:

J. H. FICKEN, Jr.,
JULIUS F. HOERIG.
